DESIGN FOR A GAME BOARD

Alves M. Melton and Cecil D. Little,
Ventura, Calif.

Application October 28, 1941, Serial No. 103,923

Term of patent 7 years

To all whom it may concern:

Be it known that we, Alves M. Melton and Cecil D. Little, citizens of the United States, residing at Ventura, in the county of Ventura and State of California, have invented a new, original, and ornamental Design for a Game Board, of which the following is a specification, reference being had to the accompanying drawing, forming part thereof.

In the aforesaid drawing:

Fig. 1 is a plan view of the game board, showing our new design.

Fig. 2 is a side elevational view thereof.

Portions of the drawing are lined for contrasting colors.

I claim:

The ornamental design for a game board, as shown and described.

ALVES M. MELTON.
CECIL D. LITTLE.
